CEILING PLENUM AND AIR CONDITIONING SYSTEM

George M. Rapp, Hamden, Conn., assignor to Houdaille Industries, Inc., Detroit, Mich., a corporation of Michigan

Application January 5, 1951, Serial No. 204,604

1 Claim. (Cl. 257—124)

The present invention relates to a ceiling plenum air-conditioning system and more particularly to a prefabricated ceiling tile unit defining an interior plenum chamber and including a heat exchanger having a perforate backing plate defining a diffusion surface.

In order to obtain greater uniformity of heat distribution within an enclosed habitable space, it has been proposed that heated or otherwise conditioned air be introduced into the space through perforate ceilings. The method of air-conditioning utilizing such a perforate ceiling includes the conditioning or heating of the air at a point remote from the enclosed space, the conveyance of this conditioned air to plenum chambers or spaces above the perforate ceiling, and then the passage or effluence of the air to the space to be conditioned through the ceiling itself.

The present invention now provides an improved form of ceiling plenum air-conditioning system wherein the air is heated or otherwise conditioned as it is diffused through the perforate ceiling into the space to be heated. More particularly, the present invention includes a plate and tube-type heat exchanger having a backing plate which is in greater than semi-peripheral contact with a heat exchange fluid conduit, preferably in the form of a sinuous tube having straight reaches thereof secured to the plate by deformation of the plate into contact therewith. The passage of heat exchange fluid through the tube will serve to heat or cool the backing plate which then provides a heat radiating or air-conditioning surface. In the present invention, the surface is apertured and air from the plenum chamber is passed through the apertured backing plate for diffusion into the space to be conditioned.

In the formation of a ceiling air-conditioning system, the heat exchanger preferably forms an integral part of a relatively shallow ceiling tile unit including a perforate backing plate bearing the heat exchanger conduits and having integral upturned marginal flanges which define relatively shallow pans. Preferably, sound absorbent material, in the form of prefabricated filler blocks, are carried by the pans intermediate the depths thereof to define a plenum chamber lying between the sound absorbent blocks and the heat exchanger diffusion surface.

The tile units are assembled in aligned, transversely spaced rows with the spaces between the tile units being utilized for the introduction of air from a desired fresh air source, air passing through the passages between the row of tile units and flowing into the plenum chambers which communicate therewith. Adjustable valve means are provided to control the flow of air into the plenum chambers, and air from the plenum chambers will be diffused downwardly through the radiant backing plate into the space to be heated. Air within the plenum chambers is heated by radiation from the backing plate, and further heating occurs upon passage of the air through the perforate backing plate itself. Sound from the space to be heated is absorbed by the sound absorbent blocks

2

disposed within the tile units, so that a dual function of air-conditioning and sound absorption is obtained.

Of course, it will be appreciated that the present invention may also be utilized as an air cooling system during the summer months with a refrigerant or similar coolant being circulated through the heat exchange fluid conduits. In this manner, year-around utilization of the ceiling is possible for improved air conditioning under any adverse weather conditions.

10 It is, therefore, an important object of the present invention to provide an improved ceiling plenum air-conditioning system utilizing a perforate heat exchange plate as a diffusion medium.

Another important object of the present invention, is 15 to provide a ceiling tile unit defining an interior plenum chamber for the reception of air from a source and having a perforate heat exchange surface defining a diffusion medium for accommodating the passage of air from the plenum chamber into a space to be heated.

20 It is a further important object of the present invention to provide a ceiling tile unit in the form of a relatively shallow pan having a sound absorbent material disposed therein in spaced relation to the pan bottom to define a plenum chamber therebetween for the reception of air 25 from a source and the pan bottom being perforated for accommodating the flow of air therethrough from the plenum chamber to a space to be conditioned.

Still another important object of the present invention is to provide a ceiling plenum air-conditioning system including a plurality of ceiling tile units each providing a plenum chamber communicating through a perforate heat exchange surface with a space to be conditioned, and airflow spaces between adjacent tile units and communicating with a source of fresh air and the plenum chambers 35 for introducing air into the plenum chambers for later diffusion through the heat exchange surface into the space to be conditioned.

Other and further important objects of this invention will be apparent from the disclosures in the specification 40 and the accompanying drawings.

On the drawings:

Figure 1 is a fragmentary plan view of a ceiling plenum air-conditioning system of the present invention;

Figure 2 is a plan view of an individual tile unit of 45 the present invention;

Figure 3 is a fragmentary, greatly enlarged sectional view taken along the plane III—III of Figure 1;

Figure 4 is a fragmentary sectional view taken along the plane IV—IV of Figure 1; and

50 Figure 5 is a schematic illustration of an air-conditioning system of the present invention illustrating the flow of air through the system.

As shown on the drawings:

55 In Figure 1, reference numeral 10 refers generally to a ceiling plenum air-conditioning system adapted to be secured to a ceiling sub-structure of an enclosed habitable space.

More particularly, the ceiling of Figure 1 is composed of a plurality of individual prefabricated composite tile units 60 11 as best illustrated in Figures 2—4, inclusive. Each tile unit 11 takes the form of a relatively shallow tray having a bottom wall 12 and upstanding marginal side flanges 13 extending along the longer longitudinal sides of the tray and transverse upturned side flanges 14 extending along the shorter sides of the trays and slotted as at 15 (Figure 65 2). The bottom wall 12 of each tray 11 is perforated, as at 16, the perforations being of any desired shape and either being merely punched, as illustrated, or punched and drawn (not shown), if desired.

The bottom walls 12 are also provided with grooves 17 which coincide at the walls 14 with the slots 15 heretofore described. The grooves 17 receive therein the

straight portions only of a sinuous length of heat exchanger tubing 18, joining portions 19 of the tubing length extending laterally beyond the edges of the bottom wall or plate 12, so that it is not necessary to provide a sinuous groove 17. Those portions of bottom plate 12 adjacent the tube groove 17 are deformed inwardly so that the plate 12 is in greater than semi-peripheral contact with the outer surface of the tube 18 along the entire length of the tube contacting the plate, these plate deformations being indicated generally at 19a (Figure 3). It will be seen that the slots 15 accommodate the extension of the joining turns 19 of the sinuous tube length 18 beyond the confines of the plate, and it will be seen that there is no interference between the plate end flange 14 and the tubing. Similarly, it will be seen that the tube 18 and the plate groove 17 extend into the interior of the tray so that a substantially smooth tray undersurface is defined by the lower wall 12.

Intermediate the depth of the tray, the longitudinal flanges 13 carry seating members 20 in the form of right-angle brackets welded, brazed, or otherwise secured to the inner surfaces of the flanges and having an in-turned upper leg 20a extending in spaced, substantially parallel relation to the bottom plate 12. The angle brackets 20 support a prefabricated, generally rectangular block 21 of sound absorbent material having its under surface 21a resting upon the angle bracket legs 20a so as to extend in parallel spaced relation to the bottom plate 12. The blocks 21 are preferably sealed about their vertical edges, as at 22, to each of the flanges 13-14 of the tile units 11. In this manner, the space A between the under surface of the block 21 and the bottom plate 12 is sealed along its upper extremity.

Inasmuch as the space A is sealed from the atmosphere thereabove by the sealing material 22 enclosing the block 21, the only communication of this space with the atmosphere is through the plate 12, so that the space A thus defines a plenum chamber directly overlying the plate 12 and communicating with the space therebeneath through the perforations thereof. Ingress to the plenum chamber A is provided by means of a plurality of slots or apertures 23 formed in those portions of the flange 14 communicating with the space A. A control for the ingress of air into the space A is provided by a valving element 24 defined by those portions of the flange 14 severed to provide the slots 23. It will be seen that the slots 23 are defined by generally three-sided incisions formed in the flanges with the severed flange portion being deflectable along its line of juncture with the flange. The degree of deflection of the portion 24 controls the amount of air introduced into the space A and thereby the amount of air which is provided for diffusion through the plate 12.

It will be seen from Figures 1, 4 and 5 that a ceiling air-conditioning system is preferably formed by the assembly of a plurality of tile units of the present invention in longitudinally aligned, transversely spaced rows. More particularly, a plurality of units 11 are assembled to define one row of tile units, and a plurality of additional units 11 are assembled in spaced relation to the first group of units to define a second row. The space 25 lying between the rows of units defines a duct common to both rows of units, and this duct preferably communicates with a primary duct 26 which in turn communicates with a source of air under differential pressure. The ducts 25 defined between adjacent rows of units 11 are provided by an imperforate dummy plate 27 having upturned lateral side flanges 28 which are so dimensioned as to be insertable into the space between adjacent rows of units 11. The dummy plate 27, being imperforate, merely serves to confine air to the duct 25 and air from the duct is permitted ingress into the plenum chambers A of the units on each side thereof through the slots 23 and the partially or completely opened valving elements 24 therefor. In this manner, air from the ducts is introduced into the plenum chambers for escape therefrom through

the perforate plates 12 which therefore serve as diffusion plates uniformly spreading air from the plenum chambers across the entire surface area of the plates.

Further, the diffusion plate 12 serves as a heat exchange surface for conditioning the air by radiation and convection, the air being first conditioned while in the chamber A and being further conditioned upon passage through and intimate contact with the plate 12. The heat exchange properties of the plate 12 will be readily appreciated by those skilled in the art, inasmuch as the plate is in extended, greater than semi-peripheral surface contact with the heat exchange tubes 18 which are adapted for connection to the source of heated or refrigerated heat exchange fluid, as desired.

The different sinuous tubes 18 of adjacent rows of tile units are interconnected as best illustrated in Figures 1 and 4, so that a constant flow of heat exchange fluid throughout the system is possible. More particularly, the terminal portions 18a of the tubes 18 extend beyond the confines of the plates 12, and these portions 18a of adjacent tile units are connected by means of couplings 28 which accommodate fluid flow between the various units.

It will be appreciated that the system of the present invention is capable of year-around use, depending upon whether the heat exchange fluid flowing through the conduits 18 is heated or refrigerated. If the fluid is heated, the plate 12 acts as a radiation surface and air passing through the diffusion plate and also contained within the plenum chamber A will be heated. On the other hand, if the heat exchange fluid flowing through the tube 18 is a coolant, a cooling effect is exerted upon air within the plenum chamber A and passing through the diffusion plate 12.

The sound absorbent properties of the block 21 also serve to deaden sound within the space to which air is being supplied to the diffusion plate 12, and the block 21 serves to isolate the plenum chamber A, so that flow therethrough is effectively directed through the plate 12. The absorbent block 21 may be of any desired sound absorbent material, numerous examples of which are well known in the art. For example, a low-density cement-aggregate mixture or ceramic material having appropriate porosity for effective sound absorption, good fugacity for water vapor, and good thermal insulating value may be employed. However, it is preferred that the material known as Microporite be utilized. This material is an indurated hydrous calcium silicate which is fully disclosed in U. S. Patent No. 1,932,971.

Where a material having water vapor fugacity properties is utilized, the block 21 also serves to automatically dehumidify air passing through the plenum chamber A, so that an additional advantage is thereby obtained. Conventional air-conditioning controls may be utilized in conjunction with the apparatus of the present invention so that truly effective conditioning action may be obtained. In order to install the tile units of the present invention upon a sub-ceiling structure, furring strips to which the flanges 13 and 14 are attached may be utilized, as is well known in the art, or the flanges 13 and 14 may terminate in flush relation with the upper extremity of the acoustic block 21, so that the units may be attached to the ceiling by means of an adhesive secured to the block 21 as is well known in the sound absorption art.

The advantages residing in applicant's invention will be readily appreciated by those skilled in the art, particularly since applicant provides means for conditioning air from a source as the air is passed through a plenum chamber and a diffusion surface. Thus, there is no heat loss or heat gain during passage of the air from its source to the diffusion plate, thus greatly increasing the air conditioning efficiency of the entire system. Further, the present invention combines its air-conditioning functions with sound absorption and automatic air dehumidification. Further, the provision of prefabricated composite

tile units makes possible the obtaining of these three functions by means of a single installation, while the utilization of standard size units makes possible the adaptation of the system to any type of existing or newly built sub-ceiling structure.

It will be understood that modifications and variations may be effected without departing from the scope of the novel concepts of the present invention.

I claim as my invention:

In a ceiling plenum air-conditioning system, a plurality of rows of conditioning units, each unit comprising: a rectangular sheet metal pan having upstanding side and end walls and having a perforate bottom wall deformed to provide a plurality of grooves in spaced parallel relation to each other and to said side walls, a length of heat exchange tubing extending sinuously on said bottom wall and including straight portions in said grooves and curved connecting portions projecting beyond said end walls with each end of said length of tubing also projecting beyond an end wall of said pan, and a block of sound absorbent material supported in said pan in spaced relation above said bottom wall and extending continuously over the entire cross section of the pan between the upstanding side and end walls thereof, said block having vertical edge surfaces sealed to said upstanding side and end walls to define therewith a plenum chamber sealed along its upper extremity, said units being disposed in aligned side-by-side relation in said rows with

5 10 15

the end walls of the units of each row in spaced relation to the end walls of the adjacent rows, a plurality of imperforate plates coplanar with said bottom walls of said units and extending between the end walls of the units of each row and the end walls of the units of the adjacent rows, means disposed above said plates for interconnecting the heat exchange tubing of the units, said plates cooperating with said end walls to define air ducts between the rows of conditioning units and space for said connecting portions of the lengths of tubing with said plates being removable from below to provide access to said tubing interconnecting means, and each of said end walls being apertured to provide communication between said air duct and the plenum chambers of the
